UNITED STATES PATENT OFFICE.

EMMA C. FARRER AND MATHEW P. FARRER, OF LORDSBURG, NEW MEXICO.

CHILD'S CARRIER AND SLEEPER.

1,210,289.

Specification of Letters Patent. Patented Dec. 26, 1916.

Application filed March 14, 1916. Serial No. 84,190.

To all whom it may concern:

Be it known that we, EMMA C. FARRER and MATHEW P. FARRER, citizens of the United States, residing at Lordsburg, in the county of Grant and State of New Mexico, have invented certain new and useful Improvements in Children's Carriers and Sleepers, of which the following is a specification.

10 This invention relates to devices for supporting a child's bed or hammock from a stationary support, for instance the back of the seat in a railway car, automobile, or other vehicle, or to the backs of two chairs, 15 and has for one of its objects to simplify and improve the construction and increase the efficiency and utility of devices of this character.

Another object of the invention is to provide a device of this character in which the parts may be separated for storage within a small space or for transportation, and quickly set up or taken down as required.

With these and other objects in view, 25 the invention consists in certain novel features of construction as hereinafter shown and described and then specifically pointed out in the claims, and in the drawings illustrative of the preferred embodiment of the 30 invention Figure 1 is a side elevation of the improved device applied to the back of a conventional railway car seat; Fig. 2 is an end elevation of the parts shown in Fig. 1; Fig. 3 is a plan view of the parts 35 shown in Figs. 1 and 2; Fig. 4 is an enlarged perspective view of one of the suspension members or hangers; Fig. 5 is an enlarged perspective view of one of the hammock supporting arms and its attachments.

Corresponding and like parts are referred to in the following description and indicated in all the views of the drawings by the same reference characters.

45 The improved device comprises suspension devices spaced apart and including a body portion 10 having a hooked upper end 11 to engage over the support, for instance the back 12 of the seat of an ordinary railway car, and a rod-like lower portion 13. Two of the members 10 will be employed and spaced apart a distance corresponding to the size or length of the hammock or other receptacle which is employed. Extending between the hangers 10 is a brace

or stay device formed in two sections 14—14' telescopically arranged and provided with terminal sockets 15—15' slidably engaging the vertical portions of the members 10. The members 14—14' are adjustably coupled by a set screw 14², while the sockets 15—15' are likewise provided with set screws 15² and 15³. By this means, the members 10 may be adjusted any distance apart and firmly held in their adjusted position. Slidably disposed upon each of the rod portions 13 is a sleeve 16 from which an arm 17 extends and terminating in a hook 18 to receive the suspension ring 19 of a hammock 20. The arms 17, together with their hooks 18, will be constructed in rights and lefts, as illustrated in Fig. 1 and directed toward each other. The sleeves 16 are each provided with a thumb screw 21 to enable them to be adjustably coupled 25 to the rod portions 13 of the hangers, to enable the hammock to be adjusted vertically within the range of the portions 13. Depending from each of the arms 17, is a leg member, comprising an upper rod 22 and 30 a lower tubular section 23 in which the rod 22 is adjustably supported and held at any required point by a thumb screw 24.

If found necessary, brace devices 25 will be pivotally united at 26 to the arms 17 35 and provided at their outer ends with a clip device 27 engaging the stay member 14 and clamped thereon by a thumb screw 28. By this means, the inward strain exerted 40 upon the arms 17, when weight is applied 90 to the hammock will be counteracted.

The improved device will be found very convenient for use by travelers with small children to enable the child to be supported while sleeping, and thus relieve the attendant from fatigue incident to the care of the child.

The parts comprising the improved device are all separable, as noted, so that the parts can be compactly arranged when not 100 in use and carried in a small hand bag or valise and quickly set up, when desired.

The hook portions 11 will be as thin as possible consistent to the strains to which they will be subjected, and being located near the end portions of the seat will not interfere with the occupants of the seat to the back of which the device is attached.

The sleeves 16 fitting the rounded portions 13 of the hangers, the arms 17 may 110

be turned in longitudinal alinement with the stay device 14—14' when not in use, to occupy less space.

Having thus described the invention, what is claimed as new is:

1. A device of the class described comprising hangers spaced apart and adapted to engage a support, a stay member connecting said hangers, an arm extending laterally from each of said hangers and adapted to support a hammock device, and braces connecting said arms to said stay member.

10 2. A device of the class described comprising hangers spaced apart and adapted to engage a support, a stay member connecting said hangers, an arm extending laterally from each of said hangers and rotatable 15

thereon and adapted to support a hammock device, braces between said stay member and arms, means for clamping said arms to said supports, and a leg device depending from the free end of each of said arms.

3. A device of the class described comprising hangers spaced apart and adapted to engage a support, a stay member connecting said hangers, an arm extending from each of said hangers and rotative 25 thereon and adapted to support a hammock device, and means for clamping said arms to said hangers.

30 In testimony whereof we affix our signatures.

EMMA C. FARRER. [L. S.]
MATHEW P. FARRER. [L. S.]
